UNITED STATES PATENT OFFICE.

FRANK E. SWANSON, OF MAPLE PLAIN, MINNESOTA.

BARREL-HANDLING DEVICE.

Application filed December 6, 1923. Serial No. 678,872.

To all whom it may concern:

Be it known that I, FRANK E. SWANSON, a citizen of the United States, residing at Maple Plain, in the county of Hennepin 5 and State of Minnesota, have invented certain new and useful Improvements in Barrel-Handling Devices; and I do hereby declare the following to be a full, clear, and exact description of the invention, such as 10 will enable others skilled in the art to which it appertains to make and use the same.

This invention relates to a device for handling barrels or similar containers. Barrels and barrel-like containers are now 15 commonly used for liquids and other materials in stores, garages, warehouses, etc. It is often necessary and desirable to move such barrels and in many cases it is customary to elevate and tilt the barrels in some 20 sort of a device for dispensing liquids therefrom.

It is an object of this invention to provide a device for elevating and tilting a barrel which can be brought into engagement with the barrel and secured thereto merely by tilting the barrel.

It is a further object of the invention to provide such a device mounted upon a wheeled frame open at one end and comprising 30 spaced longitudinal members which can be moved at each side of the barrel to bring the device into operative relation thereto.

It is still another object of the invention to provide such a frame as above mentioned 35 having mounted thereon means for gripping and supporting the barrel, together with means for swinging said means to simultaneously elevate and tilt the barrel.

These and other objects and advantages 40 of the invention will be fully set forth in the following description made in connection with the accompanying drawings in which like reference characters refer to the same parts throughout the different views, 45 and in which,

Fig. 1 is a view in side elevation of the device showing a barrel in dispensing position therein, a container for receiving the dispensed liquid also being shown;

50 Fig. 2 is a view in side elevation showing the device as it is initially applied to a barrel;

Fig. 3 is a substantially vertical section 55 taken on the line 3—3 of Fig. 2, as indicated by the arrows;

Fig. 4 is a section taken on the line 4—4 of Fig. 1, as indicated by the arrows; and

Fig. 5 is a fragmentary view in side elevation showing a modification.

Referring to the drawings, the device 60 comprises a wheeled frame having spaced longitudinal members 1 which, in the embodiment of the invention illustrated, are shown as made of angle bars, and as having secured adjacent their ends, caster wheels 65 2 and 3, the latter of which are arranged for swivelling movement. The members 1 are connected adjacent one end by one or more transverse bars 4 but are free or unconnected at their opposite ends. Rising from each 70 of the members 1 are spaced uprights 5 and 6, the latter being of greater height than the former and said uprights being connected by an inclined bar 7. The bars 7 have secured thereto adjacent their lower ends or 75 formed integrally therewith, rack members 8, on the lower end of which extends upwardly, a stop member 9. In the embodiment of the invention illustrated, the members 8 and 9 are shown as formed on a separate piece connected to the members 5 and 6 by suitable bolts or screws. A yoke or 80 cradle member 10 is provided which is of considerable width at its central portion but tapered toward its ends which are rounded 85 to form hubs. Adjacent its central portion, the yoke 10 is provided with spaced flanges 11 apertured to receive oppositely extending clamping rods 12 having hooks at their outer ends adapted to engage over the ends 90 of the barrel or container and being threaded at their inner ends and provided with suitable nuts engaging the inner sides of the flanges 11. The ends of the yoke 10 are provided with squared apertures adapted to receive a squared shaft or bolt 13 held in place by a suitable head and nut. Mounted on each shaft 13 is a pinion 14 suitably apertured to receive the shaft so as to rotate therewith. At one side of the device, 95

a geared segment 15 is mounted upon the outer end of shaft 13 to turn therewith. The segment 15 has its toothed portion eccentric to the shaft 13 and this toothed portion is engaged by a pinion 16 mounted upon the 100 squared portion of a headed and nutted bolt 17. The bolt 17 is cylindrical adjacent its head and is journaled in the members 7 and 6 at their upper ends and also in one of the handle members 20 which are secured to 105 110

and project forwardly from the members 6. The squared portion of shaft 17 also has fitted thereon the hub of a handle-equipped crank 18 by which the shaft and pinion 16 are turned. The pinion 16 is held in any desired position by the double-toothed pawl 19 pivotally mounted upon one of the handles 20. The outer end of the other shaft 13 has a hub portion 18^a thereon at 10 the outer side of pinion 14.

In operation, the device will normally be in the position shown in Fig. 2. When in such position, the frame is grasped by the handles 20 and moved adjacent the container 15 a so that the sides 1 and the yoke 10 embrace the same. The container is now tilted slightly and the rods 12 hooked over the ends thereof and tightened thereon by turning the nuts on the ends of said rods. The 20 barrel or container is thus embraced and engaged by the yoke 10 and gripped by the rods 12. The pawl 19 is now moved out of engagement with the pinion 16 and the crank 18 turned in a clock-wise direction. 25 This turning movement of the crank turns pinion 16 and through the same, turns the segment 15. As the segment 15 turns, the pinions 14 are turned therewith and moved up the racks 8. This movement of the pinions 14 on the racks 8 moves the segment 15 toward the pinion 16 so that even though the radius of the segment decreases, the teeth thereon are kept in constant engagement with the pinion 16. The turning movement 30 of the segment 15 swings the yoke 10 and rods 12 so that the barrel is tilted and the movement of the pinions 14 up the racks 8 simultaneously elevates the barrel so that the bottom edge thereof clears the floor in 40 its swinging movement. Continued turning of the crank 18 brings the barrel or container to the position shown in Fig. 1. The device can be held in this position by engagement of the pawl 19 with the pinion 16. 45 The barrel can be transported to any position with the container in the position shown in Fig. 1; or as soon as the container has been lifted from the floor.

In Fig. 5 a modification of part of applicant's device is shown. The portion corresponding to members 7, as shown in the other views, is replaced by bars 21 and 22, the bars 21 being substantially horizontal. A quadrant 23 is used which is a concentric 55 instead of an eccentric, which meshes with the gear 24, which gear is similar in all respects to the gear 14. The gear 24 is operated by the crank 25 and is supported in the standards 26 similar to the standards 6 shown in the other figures. The quadrant is 60 fixed to an eccentric 28 which carries a square shaft 27 secured in the yoke 10. In place of the gear meshing with the rack at the center of the quadrants, the eccentric 28 65 rotates in a strap 29, it, of course, being un-

derstood that there will be an eccentric 21 and strap 29 at each side of the machine just as there are gears 14 at each side in the other figures, the eccentric at the side of the machine opposite the quadrant 23 also carrying a shaft secured in the yoke 10. The straps 29 are secured to the bars 21. 70

The operation of the modification shown in Fig. 5 will be similar to that already described, except that the eccentrics 28 will 75 merely rotate on a stationary axis and will thus swing and lift the barrel, since the shaft 27 is both rotated, moved longitudinally and raised.

From the above description it is seen that 80 applicant has provided a very simple and efficient device for handling a barrel or like container. The barrel or container is engaged in the device without bodily lifting the same and the container is simultaneously 85 elevated and swung to any desired position. The parts of the device are few and simple and can be ruggedly made so that there will be little chance of the same becoming disarranged. 90

It will, of course, be understood, that various changes may be made in the form, details, arrangement and proportions of the parts without departing from the scope of applicant's invention, which, generally stated, consists in a device capable of carrying out the objects above stated and such as shown and described and set forth in the appended claims. 95

What is claimed is:

1. A barrel handling device having in combination, a yoke adapted to embrace the barrel adjacent the center thereof, means connected to said yoke clamping the ends of said barrel, said yoke having supports at each side thereof, a frame, eccentric members carried by said frame in which said supports are carried, a gear segment secured to one of said members, a pinion journaled on said frame engaging said segment, and means for turning said pinion to raise and swing said yoke, clamping means and barrel. 105

2. A barrel handling device comprising a wheeled frame having longitudinal side members spaced to pass at each side of a barrel, barrel embracing and clamping means carried by said frame in position to be engaged with said barrel when the latter is tilted, revoluble eccentric means on said frame in which said first mentioned means is carried, gearing including a crank operated member for rotating said eccentric means to simultaneously lift and swing said barrel, whereby it can be transported or its contents dispensed. 115

3. A device for handling a barrel or similar container comprising spaced longitudinally extending horizontal members, spaced vertical members upstanding from each of said horizontal members, a cradle for em- 120 125 130

- bracing a barrel having supports at each side, barrel clamping means carried by said cradle, eccentric members carried adjacent one of said vertical members and carrying 5 said yoke supports, a gear segment attached to one of said eccentric members, a pinion adjacent one of the other vertical members meshing with said gear segment, and means for rotating said pinion and holding the 10 same in position, whereby a barrel can simultaneously be lifted and rotated.
4. A device for handling a barrel or similar container having in combination, means embracing the barrel adjacent the 15 center thereof, means carried by said means for clamping the ends of the barrel, an eccentric by which said first mentioned means
- is supported, and means engaging and turning said eccentric simultaneously to raise said barrel and swing the same about a 20 transverse axis.
5. A device for handling a barrel or similar container having in combination, an arcuate band adapted to embrace the central portion of the barrel, clamping members 25 extending from said band engaging the ends of the barrel, eccentric members at the opposite ends of said band, a supporting frame on which said eccentric members rest, and crank means for turning said eccentric members whereby the barrel is simultaneously 30 lifted and swung on a transverse axis.

In testimony whereof I affix my signature.
FRANK E. SWANSON.
